UNITED STATES PATENT OFFICE.

WALTER SYDNEY ROBERTS, OF LIVERPOOL, ENGLAND, ASSIGNOR TO RAILWAY SIGNAL COMPANY LIMITED, OF WESTMINSTER, ENGLAND.

TOKEN INSTRUMENT FOR USE ON SINGLE-LINE RAILWAYS OR TRAMWAYS.

1,234,806.

Specification of Letters Patent.

Patented July 31, 1917.

Application filed July 7, 1915. Serial No. 38,622.

To all whom it may concern:

Be it known that I, WALTER SYDNEY ROBERTS, a subject of the King of Great Britain, residing at 179 Warbreck Moor, 5 Aintree, in the city of Liverpool and county of Lancaster, England, have invented new and useful Improvements in or Connected with Token Instruments for Use on Single-Line Railways or Tramways, of which the 10 following is a specification.

On sections of single lines of railways, or tramways, which are controlled by token instruments such, for instance, as those with which staffs, or the like, (hereinafter referred to as tokens), are employed and where, occasionally, or generally, the predominance of traffic over the section is in one direction, the number of tokens in the instrument at one end of the section increases while the number of tokens decreases in the corresponding instrument at the other end of the section.

In order to effect balancing, or adjusting, of the tokens between the two instruments 25 a linesman, or other person, having special authority to obtain access to the interior mechanism of the instruments, and to remove from one instrument the number of tokens required for use with the other instrument, has been employed. This is tedious and costly, especially if the authorized person be stationed at some distance away, and the number of sections which can be balanced, or adjusted, in a given time 30 is very limited. Moreover, there is the objection that one, or more, of the removed tokens may be mislaid.

This invention has for its object to overcome these objections, which is effected by 40 providing apparatus which is interlocked so that the balancing, or adjusting, of the tokens can be effected by local operators without the services of a linesman, or other specially authorized person, being required, 45 the opening of the casing, inclosing the internal mechanism of the instruments, and the withdrawal of free tokens for effecting such balancing, or adjusting, being dispensed with, while safer means are provided 50 for conveying tokens from one end of the section to the other.

In order that this invention and how it is to be performed may be well understood I will describe, with reference to the ac-

companying drawing, a construction in accordance therewith.

Figures 1 and 2 are elevations, at right angles to each other, of a magazine with its lock and key.

Figs. 3 and 4, are elevations, at right angles to each other, of a portion of a token instrument with a lock and key attached.

Figs. 5 and 6, are elevations, at right angles to each other, and Fig. 7 is a plan, showing a portion of the token instrument 65 with the magazine applied thereto. The portion of the token instrument illustrated is shown in dotted lines.

I have illustrated the said instrument as a staff instrument, and the tokens are here- 70 inafter referred to as staffs.

The same reference numerals denote like parts in the several figures.

The portion of the staff instrument shown is the column marked 6 and the 75 staffs shown therein are marked 7.

At one side of the column 6, in any suitable position, an aperture is made, as indicated at 1, this aperture being sufficiently large to allow the staffs 7, to pass length- 80 wise through it when an obstruction (such as the bolt, 2, of a lock 3, which I refer to as a lock) is removed. In this lock is an opening 5, for a key 15, carried by the magazine 10, which key, when turned in the 85 lock 3, will remove the obstruction 2, from the passage through the aperture 1.

The lock 3, carries a key 4 which passes through the opening 4^a, to enter the magazine lock 14, at 16, the said key 4, being 90 secured so that it cannot be withdrawn from the lock 3, but so that it can be passed through the lock 3, and into the magazine lock 14, when the magazine is placed in position on the instrument column.

8, is a projected piece affixed to the instrument column 6, with which piece 8, the hook 9, carried by the magazine 10, engages.

10^a, is a slot in the magazine 10, to accommodate the staffs.

In the magazine 10, is an aperture 11, in a position corresponding to the position of the aperture 1, in the instrument column 6, so that the apertures 1 and 11, coincide 105 when the magazine is applied to the instrument. Similarly to the aperture 1, this aperture 11, is large enough to allow the

staffs (indicated at 7^a) to pass through it when an obstruction, such as the bolt, 13, in the magazine lock 14, is removed, this lock 14, having in it, an opening 16, for the key 4, which has to be turned in the lock 14, to remove the obstruction 13, from the aperture 11. The aforesaid key 15, of the magazine lock is secured so that it cannot be withdrawn from the lock 14, but so that it can be passed through the lock 14, and inserted in the lock 3, when the magazine 10, is placed in position on the staff instrument.

The obstructions 2, and 13, respectively, can only be removed from the positions in which they obstruct the apertures 1 and 11, respectively, when the magazine is in position on the instrument and the apertures 1 and 11, are in alinement with each other and the opening 5, is in alinement with the magazine key 15, and the opening 16, is in alinement with the key 4. The magazine key 15, can then be inserted in the lock 3, and turned so as to remove the obstruction 2, and the key 4, can be inserted in the magazine lock 14, and turned so as to remove the obstruction 13.

When the obstructions 2 and 13, are thus removed, the staffs can be passed through the apertures 1 and 11, and from the magazine to the instrument column 6, or vice versa.

The magazine 10, cannot be removed from the staff instrument until the keys 4 and 15, are removed from their respective locks 14 and 3, and then the obstructions 2 and 13, necessarily return to their obstructive positions. The partial removal of either of the keys 4, 15, from the locks 14 and 3, respectively, will not free the magazine from the staff instrument and only when the keys 4 and 15 are turned in their respective locks 14 and 3, will the magazine be secured to the staff instrument and the obstructions 2 and 13, removed.

The lock 3, and key 4, will be alike on the respective staff instruments of the section to which the tokens apply and the magazine lock 14, and magazine key 15, will be of such a pattern as to only work in conjunction with the keys and locks of the said staff instruments.

The locks and keys for instruments and magazines for different sections should not be alike, or irregularities will be liable to occur.

The apparatus described can be operated as follows:—

Should there be a predominance of traffic over a section in one direction it becomes necessary to transfer some of the tokens, (staffs for instance) accumulated in the token instruments at one end, to the token instrument at the other end, of the section.

The magazine will then be attached to the

token instrument at the end of the section from which it is desired to remove tokens, and the required number of tokens can then be passed from the token instrument column to the magazine through the apertures from which the obstructions have been removed, and, when this has been done the said apertures are again obstructed and the magazine detached and despatched to the other end of the section and secured to the token instrument there and the tokens transferred from the magazine to the instrument, it being impossible to remove tokens from the magazine during transit.

It will therefore be seen that the transfer of tokens can readily be effected by the operators of the instruments without it being necessary to call on a specially deputed person to abstract tokens for balancing purposes.

What I claim is:—

1. In apparatus of the type described, a token-staff-receiving instrument and a portable token-staff-transfer magazine adapted to be temporarily associated therewith, said instrument and magazine having registering apertures in the associated position of the parts through which token-staffs may be manually transferred from one to the other.

2. In apparatus of the type described, a token-receiving instrument and a portable token-transfer magazine adapted to be temporarily associated therewith, said instrument and magazine having registering apertures in the associated position of the parts through which tokens may be transferred from one to the other, obstructions barring each of said apertures and means for displacing said obstructions to permit unimpeded passage of the tokens therethrough.

3. In apparatus of the type described, a token-receiving instrument and a portable token-transfer magazine adapted to be temporarily associated therewith, said instrument and magazine having registering apertures in the associated position of the parts through which tokens may be transferred from one to the other, obstructions barring said apertures and means carried by said magazine and token instrument respectively for displacing said obstructions, the means carried by the token instrument operating on the obstruction to the aperture in the magazine, and vice versa.

4. In apparatus of the type described, a token-receiving instrument and a portable token-transfer magazine adapted to be temporarily associated therewith, said instrument and magazine having registering apertures in the associated position of the parts through which tokens may be transferred from one to the other, obstructions barring said apertures and means carried by said

magazine and token instrument respectively for displacing said obstructions, the means carried by the token instrument operating on the obstruction to the aperture in the 5 magazine, and vice versa, said means serving to lock said magazine and token instrument in associated condition so long as the obstructions to said apertures are displaced.

In testimony whereof I have signed my name to this specification in the presence of 10 two subscribing witnesses.

WALTER SYDNEY ROBERTS.
